ATTORNEYS.

UNITED STATES PATENT OFFICE.

JOSEPH MEIER, OF PLAINFIELD, NEW JERSEY.

SPARK-ARRESTER.

SPECIFICATION forming part of Letters Patent No. 288,832, dated November 20, 1883.

Application filed March 8, 1883. (No model.)

To all whom it may concern:

Be it known that I, JOSEPH MEIER, of Plainfield, in the county of Union and State of New Jersey, have invented a new and Improved 5 Spark-Arrester, of which the following is a full, clear, and exact description.

The object of my invention is to provide new and improved devices for preventing sparks and cinders from being ejected out of a locomotive smoke-stack.

The invention consists in a smoke-stack constructed with two concentric tubes and two screens, and with apertures in the inner tube, above and below the lower screen, and with 15 an annular partition directly below the apertures below the lower screen and within the space between the two tubes, whereby the sparks will be arrested and will drop down through the middle tube into the smoke-box 20 again.

Reference is to be had to the accompanying drawings, forming part of this specification, in which similar letters of reference indicate corresponding parts in all the figures.

25 Figure 1 is a longitudinal sectional elevation of the upper part of a locomotive smoke-stack provided with my improved spark-arrester. Fig. 2 is an inverted sectional plan view of the same on the line *x x*, Fig. 1. Fig. 30 3 is an inverted sectional plan view of the same on the line *y y*, Fig. 1.

The smoke-stack is constructed with two concentric tubes, A B, between which an annular space, C, is formed. A short distance 35 from the upper end of the inner tube, B, a convex screen, D, is secured in the same, which screen is preferably provided with a series of short parallel slots. The tube B is provided with two series of openings, E and F, directly 40 below and above the edge, respectively, of the screen D.

On the upper end of the inner tube, B, a convex screen, G, is secured, which is preferably provided with a series of parallel slots, 45 which, however, are to be at right angles to the slots of the screen D. The edges of the screen G are extended to the outer tube, A. An annular partition, H, is arranged in the space between the two tubes A B, and below 50 the apertures E, which partition is inclined downward from the outer to the inner tube.

If desired, the smoke-stack can be provided with a hood, J, as shown.

The sparks and cinders carried upward in the pipe B, which is connected with the flue 55 from the smoke-box, strike against the screen D and are thrown down, the smoke rising through the slots or apertures of the screen D, and some passing through the apertures E into the chamber or space C, and, with the other 60 smoke, through the slots or apertures of the screen G into the hood, and then off. If any sparks or cinders pass through the screen D, they strike against the bottom of the screen G and are thrown down upon the screen D and 65 slide down the same and through the apertures F into the chamber C, and upon the partition H, down which they slide, and then pass through the apertures H into the tube B and drop to the bottom of the same. The cinders 70 are thus prevented from accumulating in the space C. The screens D G can be made straight, but are preferably made convex or conical, as a larger surface is obtained, and the sparks and cinders slide off much more readily.

Having thus described my invention, I claim as new and desire to secure by Letters Patent—

1. In a smoke-stack, the combination, with the concentric tubes A B, of the screen D in the inner tube, B, and the screen G on the upper end of the inner tube, B, and covering the annular space between the two tubes, substantially as herein shown and described, and for the purpose set forth.

2. In a smoke-stack, the combination, with 85 the outer tube, A, of the inner tube, B, and the screen D, the tube B having an annular row of apertures, E F, below and above the said screen, substantially as herein shown and described, and for the purpose set forth.

3. In a smoke-stack, the combination, with the outer tube, A, of the inner tube, B, and the screens D and G, the tube B being provided with annular rows of apertures E and F below and above the screen D, and of the annular partition H and space C between the tubes A B, substantially as herein shown and described, and for the purpose set forth.

JOSEPH MEIER.
